UNITED STATES PATENT OFFICE.

JOHN C. WAHL, OF CHICAGO, ILLINOIS, ASSIGNOR TO WAHL COMPANY, OF CHICAGO,
ILLINOIS, A CORPORATION OF DELAWARE.

CALCULATING-MACHINE.

1,325,819.

Specification of Letters Patent. Patented Dec. 23, 1919.

Application filed March 15, 1917. Serial No. 154,970.

To all whom it may concern:

Be it known that I, JOHN C. WAHL, a citizen of the United States, residing at Chicago, in the county of Cook and State 5 of Illinois, have invented certain new and useful Improvements in Calculating-Machines, of which the following is a specification.

My invention is an improved clear signal 10 for totalizer and is in the nature of an improvement on a certain co-pending application of mine now on file in the Office.

The object of my invention is to provide 15 an efficient signal for giving an indication of when a number has been completely extracted from the totalizer—in other words, to give a signal of the fact of the totalizer being at 0. In its preferred embodiment I have shown my invention attached to the 20 well-known Wahl totalizer, therefore it will not be necessary for me to describe this totalizer in detail, since it has already been described in numerous issued patents, particularly Patent No. 893,719, granted to me

25 July 21, 1908.

My invention will be best understood by reference to the accompanying drawings, of which:

Figure 1 is a view of the right side of 30 the totalizer with the supporting plate removed.

Fig. 2 is a section along the lines 2—2 of Fig. 1.

Fig. 3 is a section along the lines 3—3 35 of Fig. 1.

Fig. 4 is an enlarged view of the shutter and its operating mechanism, and

Fig. 5 is a perspective view of some parts shown in the previous figures.

As above stated, my invention is shown 40 applied to the well-known Wahl totalizer. This totalizer is usually operated in connection with a typewriter, to the numeral keys of which are attached pull rods leading 45 to an actuator which has the function of converting vertical motion of the pull rods into a differential rotation of the master wheel. The direction of rotation of the master wheel is controlled by suitable gear shift mechanism to the end that the master wheel may rotate in one direction to determine addition and in the reverse direction to determine subtraction. The totalizer is mounted on a truck which travels

with the carriage, and numbers are inserted 55 therein, digit by digit, by the rotation of the master wheel.

In the Wahl machine, prior to the rotation of the master wheel, there are certain universal actions which take place upon the 60 down stroke of any of the numeral keys. Among these actions is the counter-clockwise rotation of a certain master dog which has the double function of securely locking the typewriter carriage during the differential rotation of the master wheel, and also 65 of lifting any one of a set of swinging arms rotatably mounted in the totalizer, thus unlocking the gear chain of the totalizer and permitting the insertion of a number in 70 the totalizer at the particular decimal place in which the master wheel is then engaged. A description of the precise mechanism by which these functions are accomplished is 75 fully set forth in my hereinbefore cited patent, and I shall, therefore, start the description of my present invention with the premise that the depression of any of the numeral keys of the typewriter rotates the master wheel a differential amount, and that 80 prior to said rotation the master dog is rotated in a counter clock-wise direction to perform certain operations in the totalizer.

Referring now to Fig. 1, the master wheel 10 is rotatably mounted in the framework 85 12 on a shaft 11. Mounted on shaft 13, also rotatably mounted in the framework 12, is the master dog 14. The totalizer 15 is mounted on a traveling truck 16, which is connected to and advances step by step 90 with the motion of the typewriter carriage. The master wheel 10 is adapted to mesh with any one of a set of carrying gears 17, there being one of said gears in each decimal place of the totalizer. These carrying 95 gears are normally connected to each other by means of transfer gears 18 and 19, which are rotatably mounted on swinging arms 20 and 21, rotatably mounted on shafts 22 and 23 held between the totalizer sideplates 100 24 and 25.

Prior to the insertion of a number in the totalizer by means of the master wheel 10, the master dog 14 first lifts one of the swinging arms 20 or 21, thereby lifting the associated transfer gear 18 or 19 bodily from mesh with its associated carrying gears 17. This unlocks the chain of gearing consisting

of the carrying wheels 17 connected by the transfer gears 18 or 19 at the actuated point, leaving the gear 17 then engaged by the master wheel 10 free to be rotated and also 5 providing a locked gear chain to the highest wheel of the totalizer. The swinging arms 20 and 21 are provided at their upper extremity with a nose 26, which serves to rotate a safety bar 27 mounted on a shaft 28 10 which turns in the side plates 24 and 25. The swinging arms 20 and 21 are also provided with a locking surface 29 which is adapted to be engaged by a locking surface 30 on the safety bar when the same shall 15 have been rotated by the action of any nose 26, the object of this arrangement being to securely lock down all of the swinging arms 20 and 21, except the particular arm which has been raised by the master dog 14. It is 20 obvious from the foregoing that prior to the insertion of each digit of a number inserted by the action of the typewriter numeral keys, the safety bar 27 is rotated in a counter clock-wise direction (Fig. 1) by the action 25 of the particular swinging arm which is in mesh with the master dog 14.

Each of the carrying gears 17 has a mesh therewith and idle gear 31 rotatively mounted on a shaft 32 held between the sideplates 30 24 and 25, and in its turn each of the idle gears 31 is in mesh with a gear 33 rigid to a number disk 34, the associated gears 33 and number disks 34 being rotatively mounted on a shaft 35 held between the sideplates 24 and 35 25. The totalizer is covered by a suitable casing 36 having a window 37 therein, through which the numbers on the disks may be read.

The above described parts are all well-known parts of the Wahl totalizer. I will 40 now describe the parts which are peculiar to my present invention:

Rotatively mounted on the shaft 35 is a shutter 38, which is in the form of a bail 45 supported at either end by the shaft 35. The shutter 38 is of a width somewhat greater than the window 37, and when turned in front of said window will conceal the number wheels 34. The right-hand edge 50 of the shutter (Fig. 5) has in it a notch 39 which is engaged by a finger 40 rotatively mounted on a stud 41 riveted in the side plate 25. Rotatably mounted in the side plates 24 and 25 on a shaft 42 is a comb 43 55 having teeth 44, said teeth being in the plane of the gears 33. Each of the gears 33 is provided with a short tooth 45 and the numbers on the number disk 34 are so arranged that when the short tooth 45 is in a position to be 60 engaged by its associated comb tooth 44, the 0 will be opposite the sight opening 37. It is evident that when the zeros are all in line that the comb 43 is at liberty to turn in a counter clock-wise direction, (Fig. 1) and 65 that if any of the numeral wheels 34 do not

stand at 0, then the fact that one of the long teeth of the gear 33 being in contact with its associated comb tooth 44 will prevent the beforementioned rotation of the comb 43.

The comb 43 has on it an arm 46 to which 70 is attached a spring 47, which is fastened to a bar 48 supported between the totalizer sideplates 24 and 25. The comb 43 and its associated teeth 44 are thus urged to rotate in a counter clock-wise direction (Figs. 4 75 and 5) and are prevented from so doing except when all the short teeth 45 are in alignment, that is, when the totalizer stands at 0.

I shall now describe the means by which 80 this rotation of the comb 43 is transmitted to the finger 40, which as above noted, serves to rotate the shutter 38. Rigid to the tooth 44 at the extreme right of the comb 43 (Fig. 5) is a plate 49, having a pin 50 rigidly mounted therein. The finger 40 which, it 85 will be recalled, is rotatively mounted on the stud 41 (Fig. 5) has a slot 51 therein, which embraces the pin 50. Obviously, rotation of the comb 43 in a counter clock-wise direction will result in rotation of the finger 40 in a 90 counter clock-wise direction, and this will result in the shutter 38 being moved in front of the sight opening 37. This position of the parts is shown in Fig. 4.

The tension of the spring 47 which gives 95 the comb 43 a tendency to turn in a counter clock-wise direction (Fig. 4) will be resisted by the teeth of the gears 33. Since this friction is undesirable when said gears are turned, I have provided on the plate 49 a 100 second finger 52, which is engaged by finger 53 rigid on the safety bar 27. This results in the lifting of the comb teeth 44 out of contact with the gears 33 every time a number is inserted into the totalizer, and, since 105 it will be remembered that the safety bar 27 is rotated prior to the rotation of any of the carrying gears 17, it will be seen that when any of the totalizer gears 33 are rotated, their associated comb teeth 44 are not in contact 110 with said gears, thus the undesirable effects of the frictional engagement are avoided. I consider this feature of great importance and wish to claim the same broadly.

In the arrangement shown it is obvious 115 that the shutter 38 will be held out of line with the sight opening 37 except in the event of the totalizer standing at 0. I have colored this shutter a bright red so as to afford an effective contrast with the color of the 120 totalizer casing 36, which is usually black. Consequently when the totalizer stands at 0 a red line will be seen through the sight opening 37, the number wheels being entirely concealed in this event.

For some purposes it may be desirable to 125 reverse the action of the shutter, that is, have the shutter conceal any number which is in the totalizer and only exhibit the totalizer number wheels when these wheels stand 130

at 0. To provide for this contingency I have supplied the shutter 38 with a notch 54 which is similar to the notch 39. If the totalizer is assembled so that the finger 40 is engaged with the notch 54, then the shutter 38 will be opposite the sight opening 37 as long as there is any number in the totalizer and will disappear when the totalizer is clear.

10 This latter arrangement of the shutter is used in what is known as method of checking by means of a pre-determined total. In this method the operator writes original items into the totalizer but is not able to see 15 the total of said items. After having written the original items she then writes a total which has been given to her and writes said total in the machine in a subtracting direction. The original items have then been 20 added into the machine and the predetermined total of said items subtracted from the machine. If the predetermined total is a correct total of the items which the operator has written, the machine will then show 25 clear. This will give a check upon the accuracy of the first operator who handles these original items and determines the total thereof, and also upon the accuracy with which the second operator has written the 30 original items and the predetermined total. For, if either of the operators have made a mistake, the second machine would not show clear after the second operator had entered the original items and subtracted the predetermined total.

35 Many changes and modifications may be made in the precise mechanism herein shown, since I claim:

1. In a totalizer the combination of a totalizer including a set of gear wheels adapted to be displaced from their normal position to represent numbers, a zero determining device for mechanically determining when said gears are in their normal position, 40 means holding said determining device in contact with said gear wheels, means for inserting a number in said totalizer, and means for withdrawing said zero determining device from contact with said gears prior to 45 the insertion of a number in said totalizer.

2. In a calculating machine the combination of a totalizer including a set of numeral wheels, a zero determining device adapted to determine mechanically the zero 50 position of said numeral wheels, means to bring said zero determining device in cooperation with said numeral wheels, means to insert a number in said numeral wheels, and means to move said zero determining device 55 from its contact with said numeral wheels prior to the insertion of a number in said totalizer, whereby said numeral wheels will be free from said zero determining device during the insertion of a number in the to 60 talizer.

3. In a calculating machine the combination of a set of numeral wheels, means to rotate said numeral wheels, a zero determining device for said numeral wheels normally in contact with said wheels, and means to move 70 said zero determining device from contact with said numeral wheels prior to the rotation of said numeral wheels.

4. In a calculating machine the combination of a totalizer including a set of numeral wheels, means to insert a number therein, a zero determining device adapted to contact with said numeral wheels to determine the zero position thereof, means holding said zero determining device in contact with said wheels and means to move said zero determining device from its contact with said 75 wheels prior to the rotation of said wheels.

5. In a calculating machine the combination of a set of numeral wheels, a set of gears rotating rigidly therewith, means to rotate said numeral wheels, a zero determining device adapted to contact with said gears and thereby determining the zero position of said wheels, means for bringing said zero determining device in contact with said wheels, and means for removing said zero determining device from its contact with said gears prior to the rotation of said numeral wheels.

6. In a calculating machine the combination of a set of numeral wheels and set of gears rigidly rotated therewith, each of said gears having at least one short tooth, a zero determining device adapted to contact with said gears and thereby determine the zero 95 position for said wheels, said zero position being determined by the contact of said device with said short tooth, a spring to hold said zero determining device normally into contact with said gears, means to rotate said 100 gears and means to withdraw said zero determining device from its contact with said gears prior to the rotation of said gears.

7. In a calculating machine the combination of a set of numeral wheels, a set of 110 gears rotating rigidly therewith, said gears having at least one short tooth to determine the zero position thereof, a comb adapted to contact with said gears and by its contact with said short teeth determine their zero 115 position, a spring normally holding said comb in contact with said gears, means to rotate said gears and means to move said comb out of contact with said gears prior to the rotation of said gears.

8. In a calculating machine the combination of a set of gears adapted to represent a number by their displacement from the normal position, means to rotate said gears, a set of transfer gears normally connecting 125 said gears to thereby transfer the tens from one of said gears to the gear of the next higher order, a zero determining device adapted to determine the zero position of said gears and spring to rotate said zero 130

- 1 determining device, means to withdraw said zero determining device from its contact with said gears prior to the rotation thereof, means to withdraw one of said transfer 5 gears from its connected gears and a mechanism common to both of said last mentioned means to operate them:
9. In a calculating machine the combination of a totalizer including a set of gear 10 wheels adapted to be displaced from their normal position to represent numbers, a zero determining device for mechanically determining when said gears are in their zero position, a spring holding said determining 15 device in contact with said wheels, means for inserting a number in said totalizer and means for withdrawing said zero determining device from contact with said gears prior to the insertion of a number in said 20 totalizer and returning said zero determining device to its original position after the insertion of said number.
10. In a calculating machine the combination of a set of numeral wheels, means to 25 rotate said numeral wheels, a zero determining device for said numeral wheels normally in contact therewith, a means to move said zero determining device from contact with said numeral wheels prior to the rotation 30 of said numeral wheels and restore said device to its normal position subsequent to said rotation.
11. In a calculating machine the combination of a totalizer, including a set of 35 numeral wheels, means to insert a number therein, a zero determining device adapted to contact with said numeral wheels to determine the zero position thereof, means for holding said zero determining device in 40 contact with said wheels and means operated by said number inserting means to move said zero determining device from its contact with said wheels prior to the rotation of said wheels.
- 45 12. In a calculating machine the combination of a totalizer, including a set of numeral wheels, means to insert a number therein, a zero determining device adapted to contact with said numeral wheels to determine the zero position thereof, means holding said zero determining device in contact with said wheels and means operated by 50 said number inserting means to move said zero determining device from its contact with said wheels prior to the rotation of
- 5 said wheels and return said device to its normal position subsequent to said rotation.
13. In a calculating machine, the combination of a set of numeral wheels, means to rotate said numeral wheels, a zero determining device for said numeral wheels normally in contact therewith, means to move said zero determining device from contact with said numeral wheels prior to the rotation of said wheels, a shutter adapted to conceal 60 said numeral wheels, and means to shift said shutter co-incidently with the removal of said zero determining device from said wheels.
14. In a calculating machine, the combination of a set of numeral wheels, carrying mechanism connecting said numeral wheels, actuating mechanism adapted to insert numbers in said totalizer seriatim, a shutter co-operating with said numeral wheels, and means to rotate said shutter, said rotating means being adapted to be attached to said shutter in either of two positions to thereby reverse the cycle of operation of said shutter and operating means.
15. In a calculating machine, the combination of a set of numeral wheels, carrying mechanism connected to said numeral wheels, actuating mechanism adapted to insert a number into any of said numeral 75 wheels, whereby a number of more than one decimal place may be inserted in said numeral wheels with a less number of steps than the number of steps represented by said number, a shutter co-operating with said numeral wheels, and means to operate said shutter coincidently with the insertion of each number into the totalizer.
16. In a calculating machine, the combination of a set of numeral wheels, carrying 80 mechanism connected to said numeral wheels, actuating mechanism adapted to insert a number into any of said numeral wheels, whereby a number of more than one decimal place may be inserted in said numeral wheels with a less number of steps than the number of steps represented by said number, a shutter co-operating with said numeral wheels, and means to operate said shutter coincidently with the insertion of each digit of the number inserted into the 85 totalizer.

In witness whereof I have hereunto subscribed my name.

JOHN C. WAHL.
